MEANS FOR HEATING THE INTERIOR OF
MOTOR VEHICLES

John Edward Hiles, Hereford, England

Application July 28, 1932, Serial No. 625,287
In Great Britain July 31, 1931

1 Claim. (Cl. 237—12.3)

This invention relates to means for heating the interior of motor vehicles. When steam is employed as the heating medium it is important that the condensate is not allowed to collect in the pipes or radiators, which it is liable to do particularly where the pipes or radiators extend or are disposed below the level of the steam generator or boiler.

The object of the present invention is to provide a steam heating system having means for automatically preventing the condensed steam from collecting in the pipes or radiators, so as to prevent the same from becoming water-logged.

According to this invention the improved heating system comprises a steam generator or boiler the water of which is heated by the engine, with a steam pipe or conduit leading from the generator or boiler to the interior of the vehicle, in combination with means for creating a suction or vacuum for drawing back the condensate from the said pipe or from parts of the system, with means for returning the condensate to the steam generator or boiler. The water in the latter may be heated by the exhaust gases of the engine and the generator may, in this case, be attached to or disposed adjacent the exhaust manifold or exhaust pipe of the engine. A vacuum chamber, preferably of a large capacity, may be embodied in the system and connected to the steam pipes or conduits of the latter so that the condensate is drawn into the vacuum chamber, the said chamber being placed in communication with the steam generator or boiler, such as by a pipe or conduit, and being so disposed relatively thereto that the condensate after passing into the chamber drains back into the steam generator. The vacuum may be conveniently obtained by placing the vacuum chamber in communication with the induction pipe or induction manifold of the engine so that it is exhausted thereby.

The invention will appear more clearly from the following detailed description when taken in connection with the accompanying drawing showing the improved heating system applied to the interior of a private vehicle.

Thus, referring to the drawing, the interior of the vehicle is arranged to be heated by means of steam generated from water which is heated by the exhaust gases from the engine of the vehicle. The steam generator consists of a water chamber 1 mounted upon the exhaust manifold 2 of the engine and adapted to be filled up to a definite level, determined by the tap or cock 3, so that its upper portion extends above the water level and constitutes a steam chamber. Leading from the

top of the water chamber or steam generator 1 is a steam pipe or conduit 4 which is arranged to pass into the interior of the vehicle. This pipe 4 may be disposed inside the vehicle in any suitable way, according to where the heat is required, but may be conveniently arranged in the manner illustrated, the said pipe passing along the one side of the floor of the vehicle to the rear seat 5, where it is bent into a serpentine form and returned along the opposite side of the vehicle floor, the arrangement thus enabling the vehicle to be evenly heated as soon as the steam is generated. The portion of the pipe which is bent up into a serpentine shape may be lodged beneath the overhanging front edge of the rear seat 5 and may be entirely enclosed by means of a grid or wire mesh screen 6, thus forming a neat and efficient radiator. The steam condenses as it passes along the pipe or conduit 4, and means are provided, according to this invention, for creating a vacuum or suction which is adapted to draw the condensate from out of the said pipe and for raising it up above the boiler level where it may be allowed to drain back into the generator or boiler. For this purpose a vacuum chamber 7 is provided, preferably of a capacity larger than that of the generator 1, and the pipe or conduit 4, after passing around the interior of the vehicle, is extended upwards, the part 4a of the said pipe being connected to the vacuum chamber 7 near its upper end, so that the interior of the pipe is in communication therewith. Leading from the bottom of the vacuum chamber 7 is a pipe or conduit 8 which passes to the lower portion of the steam generator or boiler 1, so that the water which is drawn into the chamber 7 may drain back into the said generator. To enable the vacuum chamber 7 to be exhausted a suction pipe 9 is provided leading from the top of the vacuum chamber 7 to the induction pipe or induction manifold of the engine, so that during the working of the engine a constant depression or vacuum may be maintained in the vacuum chamber, with the result that the condensate which collects in the steam pipe 4 of the heating system is drawn into the vacuum chamber 7 from which it drains back into the boiler through the pipe 8, as stated. Means may be provided for cutting off the suction automatically when the vacuum chamber 7 is nearly full, and for this purpose the latter is provided with a float 13 for operating a valve 14 adapted to close the suction pipe 9 when the water reaches a certain level. An air vent normally closed by a valve 15, is provided in the top of the vacuum chamber 7, the valve 15 being 55

raised by the float to open the air vent, when the float operates the valve 14 for cutting off the suction. The vacuum or partial vacuum which is created in the chamber 7 serves to keep the 5 pipe or conduit 4 of the heating system entirely free from the condensate and the same is prevented from being waterlogged. A free circulation of the steam is thus ensured and the arrangement has the advantage of relieving the 10 system of all pressure. Moreover, as the condensate is returned to the steam generator or boiler there is little or no waste.

In order to prevent water or steam from being drawn into the vacuum chamber 7 directly from the steam generator or boiler 1 through the pipe 8, the latter may be fitted at a convenient point 15 with a check or one-way valve 10. This valve is arranged to be automatically opened in one direction by the pressure of the head of water in the vacuum chamber, to permit of the water passing to the boiler, but otherwise remains closed.

The system enables the vehicle to be heated in an efficient manner, and owing to the reduced pressure steam is quickly generated and the vehicle is soon brought to a comfortable temperature. To enable the heat to be regulated a 20 second valve 11 may be provided in the pipe 8 between the vacuum chamber and the boiler. This valve is adapted to be hand operated and by closing the valve the condensate is prevented 25 from passing back to the boiler 1 and collects in the vacuum chamber 7. The water in the boiler 1, which need be only of moderate dimensions, is thus gradually used up and the heat is 30 reduced. The temperature of the vehicle may thus be readily regulated by more or less closing this valve. Should it be desired quickly to shut off the heat the tap or cock 3 may be opened 35 so that air is then drawn into the system. If desired, provision may be made for completely emptying the boiler or steam generator.

The vacuum chamber may be used for the initial filling of the boiler, if desired, the said chamber having a suitable filler, such as 12, normally closed. The whole of the parts of the heating system may be of copper or other rust-proof 40 material, the pipes being preferably of a small diameter.

The boiler or steam generator 1 may be of a 45 cylindrical or tubular formation disposed along the top of the exhaust manifold of the engine. It may carry upon its underside flanged tubular

extensions 1* welded or fixed to the manifold; or it may be fixed to the latter in any suitable manner which provides for the efficient heating of the water. The boiler or steam generator may be of any other desired shape or construction. Any suitable means may be provided for enabling the water to be heated by the engine or exhaust gases so that it is converted into steam, with 5 pipes or conduits for conducting the latter to the interior of the vehicle, whilst a plurality of radiators connected by pipes or conduits may be provided at suitable points inside the vehicle. 10

The improved heating system may be readily adapted for large public vehicles and for all types of motor cars, as well as for aeroplanes and motor-boats. 15

Having fully described my invention, what I desire to claim and secure by Letters Patent is:—

A steam heating system for motor vehicles, comprising, in combination with an internal combustion engine having an exhaust manifold and an induction pipe; a steam generator mounted adjacent the exhaust manifold and heated thereby, a vacuum chamber disposed above the steam generator, a conduit connecting the upper part 20 of the vacuum chamber to the induction pipe, so that the vacuum chamber is exhausted by the suction of the engine, a steam conduit forming a heat radiator and extending inside the vehicle, said conduit being connected at its one end to the upper part of the vacuum chamber, so that condensed steam is drawn out of the conduit into the vacuum chamber, whilst uncondensed steam in the conduit is kept always below atmospheric 25 pressure, said conduit being connected at its opposite end to the top portion of the steam generator and extending down below the latter, and being arranged so that water from the steam generator cannot flow into the same, a float in the vacuum 30 chamber, a valve operated by the float for cutting off the suction of the engine, an air inlet in the vacuum chamber, a valve controlled by the float for opening the air inlet when the suction is cut off, a second conduit connecting the vacuum 35 chamber to the steam generator, so that the condensed steam may drain back to the latter when the air inlet is open, and a one-way valve in the second conduit preventing water from being drawn up from the steam generator into the 40 vacuum chamber. 45
